UNITED STATES PATENT OFFICE.

ROBERT IREDELL, OF AKRON, OHIO, ASSIGNOR TO THE GENERAL TIRE AND RUBBER COMPANY, OF AKRON, OHIO, A CORPORATION OF OHIO.

DESIGN FOR A VEHICLE TIRE.

Application filed August 7, 1926. Serial No. 18,638. Term of patent 14 years.

To all whom it may concern:

Be it known that I, ROBERT IREDELL, a citizen of the United States, residing at Akron, in the county of Summit, State of Ohio, have invented a new, original, and ornamental Design for a Vehicle Tire, of which the following is a specification, reference being had to the accompanying drawing, forming a part thereof.

Fig. 2 is a cross sectional view, taken substantially on line 2—2 of Fig. 1.

I claim:

The ornamental design for a vehicle tire as shown.

ROBERT IREDELL.
